STORAGE CONTAINER FOR BULK MATERIALS

William M. Cameron, Lafayette, Calif., assignor to Kaiser
Industries Corporation, a corporation of Nevada

Filed May 14, 1962, Ser. No. 70,125

Term of patent 14 years

(Cl. D58—3)

FIG-1

FIG-2FIG-3FIG-4FIG. 1 is a perspective view of the storage container for bulk materials embodying my new design;

FIG. 2 is a top plan view thereof;

FIG. 3 is a side elevational view thereof; and

FIG. 4 is a bottom view thereof.

I claim:

The ornamental design for a storage container for bulk materials, substantially as shown.
